BAG STITCHING MACHINE

Therval J. Lockwood, Gering, Nebr.

Application July 16, 1951, Serial No. 237,038

2 Claims. (Cl. 112—11)

1

This invention relates to a bag or sack sewing machine of the type used for sealing bags or sacks of sugar, salt, potatoes, and other commodities, and more particularly to means for feeding sacks to and through such a machine. The principal object of this invention is to provide a light-weight, highly efficient machine of this type which will be easily portable so that it may be easily and quickly moved to the work at hand; which can be easily adjusted to accommodate various sizes of sacks; and which will act to efficiently close and smooth the necks of the sacks preparatory to feeding them to the sewing machine or stitching head.

Another object of the invention is to provide highly efficient means for automatically starting the sewing head of the machine when a bag is in proper position to be stitched, and to provide automatic means for cutting the stitching thread and stopping the stitching head at the termination of the stitching or sewing operation.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a plan view of the improved portable bag-stitching machine;

Fig. 2 is a side view thereof;

Fig. 3 is an enlarged, vertical cross-section, taken on the line 3—3, Fig. 1;

Fig. 4 is a similarly enlarged, fragmentary, end view, illustrating a thread-cutting mechanism employed in the improved machine; and

Fig. 5 is a detail, perspective view, illustrating a machine-starting switch employed on the improved machine.

The improved bag stitcher is mounted on a rectangular base frame 10 which is portably supported upon four caster wheels 11 mounted in wheel brackets 12. The wheel brackets extend outwardly and upwardly from the extremities of the base frame 10 so as to allow the latter to be positioned in close proximity to the floor.

A sewing machine or stitching head 13 of any of the standard varieties is employed in the improved machine. The stitching head 13 is secured to and supported by an upright channel

2

member 14 arising from the rear edge of the base frame 10. The stitching head 13 is driven from an electric motor 15 through the medium of a drive belt 16 and driven pulley 17.

Four spools of stitching twine or thread 18 are supported upon spool pins 60 extending upward from a spool platform 19 supported above the upper extremity of the channel member 14 on bracket members 61. Only two of the spools 18 are in use at one time. However, by having four spools on the spool plate 19, two full spools are always available for quick replacement of two exhausted spools.

Four upright, tubular standards 20 arise from the corners of the base frame 10 in rectangular, spaced relation. An elongated conveyor frame 21 is supported by the standards 20 through the medium of set collars 22 which are vertically adjustable on the standards. The collars 22 are welded or otherwise permanently attached to the conveyor frame 21 and may be set at any desired height on the standards 20 by means of suitable set screws 23.

The conveyor frame supports two terminal belt rollers 24 between which an endless conveyor belt 25 is trained. The upper reach of

the belt slides on a belt-supporting plate, and the discharge extremity of the latter plate is inclined slightly downward, as indicated at 25'.

The feed extremity of the conveyor frame is provided with a feed platform 26, and the discharge extremity is provided with a similar delivery platform 27. The conveyor belt 25 is actuated through the medium of a suitable transmission

chain 28 extending from a suitable speed-reduction mechanism 29 which is driven by means of a second electric motor 30. The conveyor belt 25 is positioned below the needle of the stitching head 13 and acts to convey sacks or bags, such as indicated at 31, through the stitching head from the feed platform 26 to the delivery platform 27.

The discharging bags are supported and guided by means of two vertically and angularly adjustable guide arms 32 which are mounted on two of the standards 20, and which may be set in any desired position thereon by means of suitable set screws 33.

As the aligned sacks 31 travel toward the stitching head 13, the necks of the bags are gripped between two opposed, traveling, endless belts 34. Each belt 34 extends from a relatively large belt drive pulley 35 positioned at one side of the conveyor frame 21 to a relatively small, driven pulley 36 immediately alongside the

stitching head 13. The two driven pulleys are placed relatively close together so that the two belts will be held in substantial contact with each other. They are maintained in contact for a portion of their length by means of two idler pulleys 56, which are rotatably supported in an inverted, U-shaped yoke 55 supported from a supporting frame 38. Each of the idler pulleys 56 is combined with a resilient press roller 59 positioned above the pulley. The press rollers are in substantial, horizontal alignment with the needle of the stitching head 13 and act to press and smooth out any wrinkles or folds in the necks of the sacks before the latter pass into the embrace of the two gripping belts 34.

The drive pulleys 35 are mounted on vertical drive shafts 37 journaled in the supporting frame 38 at each side of the conveyor frame 21. The shafts 37 are driven in opposite directions by means of sets of suitable bevel gears 39 from a horizontal, transversally-extending gear shaft 40 journaled in the base 10. The gear shaft 40 is driven in any desired manner, such as by means of a drive chain 41 extending to the speed reducer 29 so that the motor 36 will operate both the gripping belts 34 and the conveyor belt 25.

As the sacks approach the stitching head 13, they engage a feeler lever 42 which is adjustably mounted on the lower extremity of a vertical switch-operating shaft 43. The switch-operating shaft is rotatably supported in the angle iron frame 38 and extends downwardly to a position alongside the path of the entering sacks. A cylindrical cam member 44 is mounted on the upper extremity of the shaft 43. The edge of the cam member 44 is inclined, as shown at 64, and rides beneath and supports one extremity of a hinged switch-supporting member 45. The other extremity of the switch-supporting member is hingedly mounted, as shown at 46. The member 45 carries a conventional, circuit-closing, mercury switch 47 which is connected in circuit with the stitching head motor 15. Thus, when the feeler lever 42 is swung toward the stitching head 13 by the advancing sacks, the raised portion of the cam member 44 will slide beneath the switch-supporting member 45 to tilt the mercury switch 47 so as to cause the latter to close the circuit to the stitching head motor 15 to start operation of the stitching head 13. When the sack has passed completely through the stitching head 13, it will release the feeler lever 42 and allow a return spring 48 to return the feeler lever 42 to its "off" position to receive the next sack. The return movement of the feeler lever will rotate the cam member 44 to allow the mercury switch 47 to return to its tilted, open-circuit position. Suitable stops 63 are provided on the cam member 44 which contact the sides of the switch-supporting member to limit the arc of movement thereof. The cam-actuated switch mechanism illustrated in Fig. 5 is enclosed in a suitable protective housing 54 on the complete machine.

Stitching heads of the type used on bag-closing devices are provided with power-operated, thread-cutting knives which function during the operation of the sewing head. These knives are a part of the stitching head, and form, per se, no part of this invention. The normal position of these knives is indicated on the drawing by the numeral 49. In the usual machine the operator pushes the thread, indicated at 58, forwardly into the knives to sever the last-stitched bag from the stitching head or from the next bag being stitched. In this invention the thread is pushed

into the knives automatically by means of a solenoid plunger 50 having a thread-engaging head 51. The head 51 is retracted out of the normal path of the thread by means of an electric solenoid 52 and the head 51 is forced forwardly into contact with the thread by means of a compression spring 53. The solenoid 52 is connected in the circuit to the stitching head motor 15.

Thus, whenever the motor circuit is closed to start the stitching head 13, the solenoid 52 will be energized to retract the plunger 50 and the head 51. When the stitched bag has passed completely through the stitching head 13, the motor circuit will be broken at the mercury switch 47 to de-energize the solenoid 52, allowing the spring 53 to force the shoe 51 into engagement with the thread so as to force the latter into the cutting knives 49 to sever the thread. It will be noted that the motor circuit is broken at the same time the solenoid is de-energized, but the stitching head will continue to coast for a sufficient interval to operate the cutting knives.

It can be seen from the above description that the wheels 11 allow the entire machine to be quickly and easily moved to the job, and that the set screws 23 allow the conveyor frame 21 to be easily adjusted vertically so as to bring sacks of any given size into alignment with the stitching head 13.

It will also be noted that it is unnecessary for the operator to attend the machine other than to place the open sacks on the belt 25. The machine will automatically start whenever a sack approaches the stitching head, and will automatically stop and sever the stitching twine whenever the stitching operation is completed.

The inclined portion 25' of the discharging extremity of the conveyor belt 25 tilts the tops of the sacks away from the stitching head as they emerge from the latter. The purpose of this tilting action is to tighten the thread between the last-stitched sack and the stitching head so that it will be in proper position to be engaged by the spring-actuated head 51 on the solenoid plunger 50. If the conveyor were horizontal throughout its length the sacks would remain approximately vertical, and the threads connecting the successive sacks might bow downwardly as they leave the stitching head so that they would not be engaged by the head 51 and would not be pushed into the cutting knives 49. The supporting frame 38 is held in proper space relation with the stitching head by means of a suitable tie brace 57.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. Automatic means for starting a motor driving a stitching head on a bag stitching machine comprising: a feeler lever positioned to be contacted by said bags; a switch operating shaft supporting said lever and extending upwardly therefrom; a cylindrical cam member concentrically mounted on the upper extremity of said shaft and having an upwardly-extending cam-shaped periphery; a tiltable switch supporting member hingedly mounted at its one extremity adjacent said cam member and resting adjacent its free extremity upon said cam-shaped periphery; a circuit closing mercury switch in circuit

with said motor mounted upon said tiltable switch supporting member so that when said feeler arm rotates said cam member, through the medium of said shaft, said cam-shaped periphery will move beneath said switch member to tilt the latter to cause said mercury switch to close the circuit to said stitching head motor to start a line of stitching across and connected to said bag.

2. Automatic means for starting a motor driving a stitching head on a bag stitching machine as described in claim 1, having thread cutting blades operable by said stitching head and positioned at one side of the line of stitching connected to said bag; a plunger positioned on the opposite side of said line of stitching from said cutting blades; a spring urging said plunger against the line of stitching to force the latter into cutting engagement with said cutting blades; and an electrode solenoid adapted to

withdraw said plunger from engagement with said line of stitching against the action of said spring, said solenoid being in circuit with said mercury switch so as to be energized simultaneously with said stitching head motor.
